UNITED STATES PATENT OFFICE

148,184

DESIGN FOR A COMBINATION RECORD PLAYER AND RADIO

Clyde A. Peterson, Lewisburg, Pa., assignor to
Westinghouse Electric Corporation, a corpora-
tion of Pennsylvania

Application August 22, 1946, Serial No. 132,730

Term of patent 7 years

(Cl. D56—4)

To all whom it may concern:

Be it known that I, Clyde A. Peterson, a citizen of the United States, residing at Lewisburg, in the county of Union and State of Pennsylvania, have invented a new, original, and ornamental Design for a Combination Record Player and Radio, of which the following is a specification, reference being had to the accompanying drawings, forming a part thereof, in which the figure is a front perspective view of a combination record player and radio receiver embodying my new design.

The right-hand end portion is similar in appearance to the end shown in the drawings. The rear portion is plain.

The dominant features of my new design are shown by means of full lines in the drawings.

I claim:

The ornamental design for a combination record player and radio, substantially as shown and described.

CLYDE A. PETERSON.
